UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

DOOR-OPERATING MECHANISM

Application filed June 10, 1926. Serial No. 115,061.

This invention relates to door operating mechanisms.

An object of the invention is to provide a simple and efficient door operating mechanism for forcing the door when partly closed to tightly closed position, for holding the same closed, and for forcing the door open to facilitate complete opening of the same.

Another object of the invention is to provide a mechanism of the character described, especially designed for operating doors of the swinging type, including an integral operating bar fulcrumed upon the door intermediate its ends and mounted for longitudinal reciprocation, together with keepers secured to the door frame which cooperate with the operating bar to effect opening and closing movement of the door, means being provided which initially swing the operating member about its fulcrum to force the door in opening and closing directions, and thereafter during opening movement of the door reciprocates said bar upwardly so that the lower end thereof is retracted from its projecting position below the lower edge of the door in order that said edge will be free of depending projections so as to clear the usual car loading platform.

Other objects of my invention will more clearly appear from the description and claims hereinafter following.

In the drawings forming a part of this specification, Fig. 1 is a side elevation of a portion of a refrigerator car showing my improvements in connection therewith. Fig. 2 is a vertical, sectional view on an enlarged scale, partly broken away, corresponding substantially to the line 2—2 of Fig. 1. Fig. 3 is a part sectional, part elevational view of the lower keeper and end of the operating bar, taken substantially upon the line 3—3 of Fig. 2. And Fig. 4 is a sectional view taken substantially upon the line 4—4 of Fig. 1.

In said drawings, the side of the car is shown as provided with a door frame 10 and two pivoted doors 11 and 12. The doors have the usual bevelled meeting edges and the customary insulation or packing is employed

themselves, and between the doors and the door frame. The doors 11 and 12 are mounted for swinging movement about vertical axes, being supported by suitable hinges 13—13.

The invention comprises broadly an operating bar or member A; keepers B—B; and actuating mechanism C.

The door operating member A is in the form of a substantially flat bar of rectangular cross section having its opposite ends bevelled as best shown in Fig. 3. The bar A is preferably disposed vertically of the door 12 and adjacent the inner edge thereof, and said bar is fulcrumed intermediate its ends and slidably mounted upon the door by means of the bracket 14. Said bracket comprises a base plate 15 and outer strap 16, said strap and plate being secured in position by suitable bolts indicated at 17—17. Upon each of the bolts 17, at opposite sides of the bar A, between the strap 16 and plate 15, are mounted anti-friction rollers 18—18, said rollers providing a fulcrum intermediate the ends of the bar A, and permitting vertical reciprocation thereof. A guide bracket 19 is secured to the door 12 adjacent the upper edge thereof and confines the upper end portion of the bar A to movement in a plane substantially parallel to the plane of the door 12, while permitting swinging of said end with respect thereto and permitting vertical reciprocation of the bar A. The lower end of the bar A is movably confined in a support which encases a portion of the actuating mechanism C hereinafter described.

The keepers B—B are two in number, one being secured to the door frame above the top edge of the door 12, and the other being secured to the door frame below the bottom edge of the door 12. The lower keeper comprises a member having flanges 20 and 21 through which are extended securing bolts for fixing the keeper in position. The lower keeper is also provided with a bottom wall 22 and with upstanding portions providing cam surfaces defining a cam slot 23, which slot is inclined at an angle to the plane of the door frame and is adapted for the reception of the lower end of the operating bar

A. The lower keeper is so arranged that the slot 23 opens outwardly toward the forward edge of the door 12 as shown. The upper keeper is identically similar to the lower keeper thus far described, except that instead of the cam slot opening outwardly toward the edge of the door 12, as in the case of the lower keeper, the cam slot opens in the opposite direction or away from the free edge of the door 12, as indicated at 24. The upper keeper also differs from the lower keeper in that the wall which would correspond to the lower wall 22 of the lower keeper, is omitted so as to permit reciprocatory movement of the upper end of the operating bar upwardly past the keeper as indicated in dotted lines of Fig. 1 in certain positions of the parts.

The flange portion 21 of the lower keeper is extended to the left as shown in Fig. 1 beyond the free edge of the door 12, and has pivotally mounted thereon a latch member 25 adapted to coact with a plate 26 secured to the door 11 adjacent the lower right hand corner thereof. The latch 25 serves to retain the door 11 in position when closed. The latch 25 is provided with a laterally extending flange 27 having an opening therein adapted to cooperate with a latch mounted upon the actuating means C as hereinafter described.

Mounted at the lower left hand corner of the door 12 is the actuating mechanism C. Said mechanism includes a support 28 rigidly secured to the door 12 by suitable bolts, said support including an outer wall 29 spaced from the door 12. The top edge of said wall is rounded, and at a suitable point on said edge there is provided a projection 280 for a purpose hereinafter described. The inner surface of the wall 29 is provided with an L-shaped slot 30, one portion of said slot extending in a horizontal direction, and the remaining portion extending vertically, as best seen in dotted lines in Fig. 1. Pivotally mounted upon the outer wall 29 by means of a pivot pin 31 is an operating lever 32. Said lever is provided at the side of the pivot pin 31 opposite to the handle of the lever, with an angular portion 33, the angular portion of the lever having a slot 34 formed therein. Fixed upon the lower end of the member A is a pin 35 which projects through the slot 34 in the angular portion of the lever, and into the L-shaped slot 30 formed in the inner surface of the wall 29. The handle of the lever extends outwardly from the housing, and mounted upon said handle is a gravity latch 36, said latch being provided with a lateral flange having an opening therein adapted to coincide with the opening in the flange of the latch 25, to permit the insertion of a securing member when the door is closed.

In operation assuming the doors to be closed as shown in Fig. 1 of the drawings and that it is desired to open the same, gravity

latch 36 is first disconnected, after which the lever 32 is swung in a clockwise direction about its pivot 31. This movement of the lever effects clockwise movement of the angular portion 33 of the lever and carries therewith the pin 35 which is fixed to the lower end of the bar A in a horizontal direction which causes swinging of the member A about the fulcrum 14 and the ends thereof in opposite directions and by reason of the traverse of said ends along the cam slots in the keepers, the door is forced in an opening direction. Further movement of the lever 32 causes additional travel of the angular portion thereof which lifts the pin 35 on the member A along the vertical portion of the slot 30, resulting in elevation of the bar A, the longitudinal movement of the bar being permitted by its slideable connection with the fulcrum member 14. When the lever 32 has elevated the bar sufficiently to clear the lower edge of the door, the gravity latch 36 which during the latter portion of movement of the lever has ridden over the projection 280 then falls behind said projection and prevents return of the lever toward its initial position and thereby maintains the bar A in elevated relation. The door 12 may now be easily swung completely open, and the door 11 also may be easily opened after disengaging the latch 27 by swinging it to its depending position.

When it is desired to close the doors, the door 11 is first swung in a closing direction, after which the door 12 is moved toward closed position. The gravity latch 36 is then disengaged to permit the descent of the bar A until the ends thereof are in position to enter the cam slots in the keepers. Further movement of the lever 32 in a counter-clockwise direction will effect counter-clockwise swinging of the opposite ends of the bar A, which traversing the cam slots of the keeper will force the doors in a closing direction, after which the latch 27 may be engaged to hold the door 11 closed, and the latch 36 may be secured thereto.

While I have herein shown and described what I now consider the preferred manner of carrying out the invention, the same is merely illustrative, and I contemplate all changes and modifications that come within the scope of the claims appended hereto.

I claim:

1. In a door operating mechanism of the character described, the combination with a door frame and a pivoted door; of a continuously rigid operating member fulcrumed intermediate its ends for swinging movement; keeper means on said frame adjacent opposite edges of said door for cooperation with the opposite ends of said member during the swinging movement thereof for effecting opening and closing movement of said door; and means for longitudinally shifting said member to retract the projecting edge thereof.

at the lower portion of said door to a position within the confines of the door.

2. In a door operating mechanism, the combination with a door frame and a pivoted door; of an elongated, continuous, operating member, mounted on said door for combined lateral and longitudinal movement; keeper means on said frame adapted to co-act with keeper engaging means at the upper and lower ends of said operating member, to effect opening and closing of the door; operating means for swinging said operating member in a plane parallel to the door to effect opening and closing of the door and then reciprocating said operating member lengthwise and lift the lower end thereof above the lower edge of the door; and guide means for said operating member to produce the swinging and reciprocable movement thereof, successively, while said operating means is moved in one direction.

3. In a door operating mechanism, the combination with a door frame and a pivoted door; of a unitary operating member mounted on said door; keeper means mounted on said frame, simultaneously engageable by the opposite ends of said operating member and having cam surfaces extending in a direction so that the swinging movement of the operating member causes traverse of said cam surfaces to effect opening and closing movements of the door; lever means pivoted on the door for actuating said operating member; guide means fixed to the door between the ends of the bar, in which the bar is both slideable lengthwise and swingable transversely across the face of the door; and cooperating means on said lever and member for initially swinging said operating member to cause said traverse of said keepers and thereafter reciprocating said operating member lengthwise to shift the position thereof relative to the door upon said lever means being moved in one direction.

4. In a door operating mechanism, the combination with a door frame and a pivoted door; of an operating bar mounted on said door for reciprocable and swinging movement, the upper end of said bar projecting beyond the door in all positions thereof, the lower end of said bar in one position thereof adapted to project outwardly from the lower edge of said door; keeper means mounted on said frame and adapted to co-act with the upper end of said bar and with the lower end thereof when projected and during the swinging movements of the bar to effect opening and closing movements of the door; lever means for swinging said bar during a portion of its action to cause traverse of said keepers, and during another portion of its action reciprocating said bar to shift the position thereof relative to said door, to withdraw the projecting end thereof within the confines of the lower edge of said door, said

lever means being movable in the same direction throughout said operation; and means operable when said operating member is shifted with respect to said door for automatically locking the same in its shifted position.

5. In a door operating mechanism, the combination with a door frame and a pivoted door; of keeper means mounted on said door frame; an operating lever having the opposite ends thereof co-operating with said keeper means; means for mounting said operating bar between the ends thereof on said door, said means including a fixed bracket through which the bar extends, to confine said bar to sliding and swinging movement in said bracket; anti-friction elements in said bracket arranged at opposite sides of the bar; and means for imparting successive swinging and longitudinal movements to said bar to cause traverse of said keepers to effect opening and closing movements of said door and shift the position of said bar relative to the door.

6. In a door operating mechanism of the character described, the combination with a door frame and a pivoted door; of a bracket mounted on said door and provided with a slot having communicating horizontal and vertical portions; an operating bar; means on said door between the ends of said bar for pivotally and slideably mounting the same on the door; a pin fixed to said bar and slideable in said slot; a lever pivoted to said door and also pivotally connected with said pin to cause the same to traverse said slot; and keeper means mounted on said frame and adapted to co-act with the ends of said operating bar to effect opening and closing movements of said door during movement of said bar, and lift the bar while said pin is traversing the horizontal and vertical portions of said slot.

In witness that I claim the foregoing I have hereunto subscribed my name this 25th day of May, 1926.
